STEP-UP MECHANISM

William Patzer, Chicago, Ill., assignor to Clarence E. Threedy, Chicago, Ill., as trustee

Application October 6, 1951, Serial No. 250,076

4 Claims. (Cl. 74—128)

1

This invention relates to a step-up mechanism and has for its principal object the provision of an improved construction which will be highly efficient in use and economical in manufacture.

Another and equally important object of the invention is the provision of a simplified and improved construction for step-up mechanisms which operate vending machines by the use of one or more coins of different denominations.

A still further object of the invention is to provide a step-up mechanism of the class hereinafter described which will be simple and effective in use, and compact so as to occupy a limited amount of space within the machine wherein it is employed.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is an elevational view of my improved step-up mechanism;

Fig. 2 is a side elevational view of my invention taken substantially on lines 2—2 of Fig. 1;

Fig. 3 is a side elevational view of my invention taken substantially on lines 3—3 of Fig. 1;

Fig. 4 is an elevational view similar to Fig. 1 but with the parts in different position with respect to each other;

Fig. 5 is an elevational view similar to Fig. 1 but with the parts in different relation with respect to each other;

Fig. 6 is a suggested circuit diagram for use in my improved invention; and

Fig. 7 is a diagrammatical view of a standard contact bearing disc and rotary wiper blade.

The several objects of the invention are accomplished by the preferred form of construction shown in the accompanying drawings. In these drawings a mounting plate is indicated at 10. This plate 10 is mounted to a stationary wall of the vending machine with which it is associated (not shown).

The plate 10 has journaled therein a shaft 12. Connected to the outer end of the shaft 12 is a ratchet wheel 13. The opposite end of the shaft 12, to the rear of the plate 10, terminates in a contact bearing disc 14 and wiper blade 15. The ratchet wheel 13 is connected to the shaft 12 for anticlockwise rotation against the action of a clock spring 16. Such anticlockwise rotation of the ratchet wheel 13 imparts movement to the wiper blade 15 through the shaft 12.

so that the wiper blade 15 will move over the contact heads 17 of the contact bearing disc 14. Connected to the plate 10 as at 18 for pivotal movement thereon is an actuating bar 19. Pivotedly connected to the center of the actuating bar 19, by any suitable means, is a notched arm 20 forming an extension of the plunger 21 of a master solenoid 22. The master solenoid 22 is connected to the plate 10 as at 23, below and in spaced relation to the ratchet wheel 13. The actuating bar 19 has pivotally secured thereto as at 24' a step-up pawl 24, which is adapted to engage the teeth 25 of the ratchet wheel 13. The step-up pawl 24 is held in engagement with the teeth 25 of the ratchet wheel 13 by a tension spring 26, one end of which is secured to the step-up pawl 24 as at 27, with its opposite end secured to the actuating bar 19 as at 28. The arrangement is such that when the master solenoid 22 is energized by the closing of a coin-actuating switch (switch Z as shown in the circuit diagram, Fig. 6), the plunger 21 draws the actuating bar 19 downwardly against the action of the tension spring 26, pulling the step-up pawl 24 over the teeth 25 of the ratchet wheel 13 a predetermined number of steps. Upon deenergization of the solenoid 22, the step-up pawl 24 steps up the ratchet wheel 13 under the action of the tension spring 26. The upper end of the step-up pawl 24 terminates in a bifurcation 30, which purpose will hereinafter be described.

On the plate 10 below the ratchet wheel 13 and to either side of the master solenoid 22, are blocking coils 32 and 33. These coils are secured to the plate as at 10' by any suitable means, such as by screws, etc. These blocking coils have armatures 34 and 35, pivotally connected to the plate 10 as at 32' and 33'. These armatures 34 and 35 are U-shaped at one end, with the other ends terminating in blocking fingers 36 and 37 which are parallel and in spaced relation to the plunger 21 of the master solenoid 22. Protruding through holes 38 and 39 in the plate 10 are switch fingers 40 and 41 of switches 40' and 41' which are located on the reverse side of the plate 10. These switch fingers 40 and 41 extend outwardly from the plate 10 and are bracketed by the U-shaped ends 42 and 42' of the armatures 34 and 35 of the blocking coils 32 and 33. The blocking fingers 36 and 37 are held out of engagement with the notched arm 20 by a tension spring 43, secured to the base of the blocking fingers 36 and 37, below their point of pivotal connection, 32' and 33'.

Located on the plate 10 and below the coils 32

2

and 33 are stop pins 38' which prevent engagement of the armatures 34 and 35 and the switch fingers 40 and 41 by action of the spring 43.

The arrangement is such (taking for example the blocking coil 32) that when the switch Y is closed by a coin of chosen dimension, such as a five-cent coin, this switch Y energizes the coil 32 and moves the armature 34 towards the coil. The armature 34, pivoting at its connection 32', will move the blocking finger 36 against the notch arm 20 so that the end of the blocking fingers 36 will engage the notched portion 36' of the arm 20. At the same time, but after the completed movement of the blocking finger 36, the U-shaped end 42 engages the switch finger 40 and closes the switch 40', which in turn energizes the master solenoid 22, with which it is in circuit. The energization of the master solenoid 22 pulls the plunger 21 and the notched arm 20 in a downward direction, such movement 20 being limited by the engagement of the blocking fingers 36 in the notch 36', so as to limit the movement of the step-up pawl 24 over the teeth 25 of the ratchet wheel 13, as seen in dotted lines, Fig. 5.

The same function is found in the operation of switch X with the exception that this switch is energized by a switch actuated by a coin of a different denomination, for example, a ten-cent coin, than was switch Y. Also, due to the fact that the notches 36' on the side of the arm 20 of the armature 21 are offset with respect to each other, such that one is lower than the other, the lower notch will afford more movement of the armature 21 which in turn will allow the 35 step-up pawl 24 to pass over more teeth 25 of the ratchet wheel 13, as seen in dotted lines of Fig. 4. Upon deposit of a five-cent coin, the step-up pawl 24 will move down one tooth, whereas, upon deposit of a ten-cent coin, the 40 pawl 24 will move over two teeth, and for the twenty-five cent coin, the pawl 24 will move over five teeth.

Secured as at 45 to the plate 10 is a reset coil 46. This reset coil is operated by an independent manual switch and circuit as shown in Fig. 4. Attached to the outer end of the plunger 47 of this reset coil 46, is a link connection 48 that passes upwardly through a hole 49 in the blocking coil armature 35 to the rear of the actuating bar 19 and beyond the bar where it is connected to an arm of a holding dog 50, which is pivotally secured as at 51 to the plate 10. This holding dog 50 is adapted to engage the teeth 25 of the ratchet wheel 13 so as to prevent clockwise rotation thereof. When the reset coil 46 is energized, the plunger 47 is forced outwardly, moving the link connection 48 upwardly and pivoting the holding dog 50 against the action of the tension spring 52, out of engagement with the teeth 25 of the ratchet wheel 13.

Connected to the head of the holding dog 50, is another link connection 53 that runs across the top of the ratchet wheel 13 to a member 55 pivotally secured as at 56 to the plate 10. On this pivotal member 55 is a protruding stud 57 which slidably engages the bifurcation 30 of the step-up pawl 24, so that when the reset coil 46 is energized and the holding dog 50 is disengaged from the ratchet wheel 13, movement of the link connection 53 will pivot the member 55 and its stud 57 into the bifurcation 30 and pivot the step-up pawl 24 on its pivotal connection 24' out of engagement with the ratchet wheel 13, to permit the wheel 13 to return to its starting or zero

position, under the tension of the clock spring 16.

The operation of my improved step-up mechanism is as follows:

The wheel 13 is advanced step-by-step in an anticlockwise direction through the step-up pawl 24. This is accomplished as follows:

When the switch Z, which is illustrated as a twenty-five cent coin-actuated switch (Fig. 6) is closed, the master solenoid 22 will be energized and draw the plunger 21 and the actuating bar 19 with the step-up pawl 24 attached thereto in a downward direction, causing the pawl 24 to pass over a predetermined number of teeth 25 of the wheel 13. In this instance the twenty-five cent coin will cause the pawl 24 to pass over five teeth of the wheel, to afford a step-up of five, as viewed in dotted lines, Fig. 1.

Upon deenergization of the master solenoid 22, the actuating bar 19 with the step-up pawl 24 in engagement with the teeth 25 of the wheel 13, will be drawn upward to starting position under the tension of the spring 26, causing the step-up to take place. Simultaneously with this movement the holding dog 50 will ride over the teeth 25 of the wheel 13 at the back edges of the teeth 25 of the wheel 13 form a cam surface over which the holding dog 50 will ride. Movement of the wheel 13 will be imparted to the shaft 12 to which it is secured, and the shaft 12 will in turn move the wiper blade 15 over the contact heads 17 of the disc 14.

When the blocking coil 33 is energized by the coin switch Y (illustrated here as a ten-cent coin switch), the armature 35 is drawn upward, pivoting the blocking finger 37 into engagement with the plunger 21 of the master solenoid 22, so as to cause the blocking fingers 37 to ride in the notched portion 36' of said plunger, while in the same movement of the armature 35, but after the blocking finger 37 is adjacent the arm 20 of the plunger 21, the U-shaped bracket 42 encompassing the switch finger 41 will cause the switch 41' to close, whereby to close the circuit to the master solenoid 22, causing the plunger 21 to perform its function, but with the movement thereof limited by the blocking finger 37 riding into the notched portion 36' of the arm 20 so as to cause the step-up pawl 24 to move over only two of the teeth 25 of the wheel 13, as viewed in dotted lines, Fig. 4.

The same operation takes place when the five-cent coin-actuated switch X is closed and the blocking coil 32 energized. The movement of the step-up pawl 24 over the teeth 25 of the wheel 13 is then limited to one tooth, as viewed in dotted lines, Fig. 5.

The same operation can be traced out in the diagram of the suggested circuit as viewed in Fig. 6.

After the ratchet wheel 13 has made a complete revolution, and is stopped from further movement by the stop stud 58 located on the plate 10 and which engages a stop stud 58' on the back of the wheel 13, the reset coil 46 may be energized, thereby causing the reset armature 47 to be projected out of the coil 46. Corresponding movement through the link connections 48 and 53 will thus be transmitted to the holding dog 50, to disengage the dog from the wheel, and to pivot the member 55 which, through its stud 57, will pivot the step-up pawl 24 out of engagement with the teeth 25 of the wheel 13. After the disengagement of these elements the wheel 13 is free to return to its start-

ing or zero position under the tension of the clock spring 16.

While I have illustrated and described the preferred form of construction for carrying my invention into effect, this is capable of variation and modification without departing from the spirit of the invention, I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A device of the class described comprising a supporting structure, a shaft rotatably carried by the structure, a ratchet wheel carried by and rotatable with said shaft, an actuating bar pivotally carried by said support, a step-up pawl pivotally connected to said actuating bar, said pawl engageable with said wheel for advancing said wheel a predetermined number of steps, electromagnetic means including a plunger pivotally connected to said bar and adapted to actuate said bar to advance said pawl over said wheel, said plunger having notches formed on opposite sides thereof with one of said notches offset with respect to the other to provide shoulders at substantially different levels with respect to the length of said plunger, means engageable with said shoulders to vary the position of engagement of said pawl with said wheel, and a holding dog engageable with said wheel to hold said wheel against rotation in a direction opposite to the movement of said wheel by said pawl.

2. A device of the class described comprising a supporting structure, a shaft rotatably carried by the structure, a ratchet wheel carried by and rotatable with said shaft, an actuating bar pivotally carried by said structure, a step-up pawl pivotally connected to said actuating bar, said pawl engageable with said wheel for advancing said wheel a predetermined number of steps, electromagnetic means including a plunger pivotally connected to said bar and adapted to actuate said bar to advance said pawl over said wheel, said plunger having notches formed on opposite sides thereof and offset with respect to each other to provide shoulders at substantially different levels with respect to the length of the plunger, blocking fingers pivotally connected to said structure and engageable with said shoulders, means for actuating said fingers to pivot the fingers into engagement with said shoulders to limit movement of said plunger so as to vary the position of engagement of said pawl with said wheel, and a holding dog engageable with said wheel to hold said wheel against rotation in a direction opposite to the movement of said wheel by said pawl.

3. A device of the class described comprising a supporting structure, a shaft rotatably carried by said structure, a ratchet wheel carried by and rotatable with said shaft, an actuating bar pivotally carried by said structure, a step-up pawl pivotally connected to said actuating bar, said pawl engageable with said wheel for advancing said wheel a predetermined number of steps, electromagnetic means providing a plunger pivotally connected to said actuating bar, said electromagnetic means adapted to actuate said bar through said plunger to advance said pawl over said wheel, said plunger having a notch formed in one side thereof to provide a shoulder, a blocking finger pivotally carried by said structure and having an end portion engageable with said shoulder, means for actuating said finger to engage said end portion with said shoulder to block said plunger to limit movement of the latter by said electromagnetic means, means for successively actuating said finger and said plunger, holding means engageable with said wheel to hold said wheel against rotation in a direction opposite to the movement of said wheel by said pawl.

4. A device of the class described comprising a supporting structure, a shaft rotatably carried by said structure, a ratchet wheel carried by and rotatable with said shaft, an actuating bar pivotally carried by said structure, a step-up pawl pivotally connected to said actuating bar, said pawl engageable with said wheel for advancing said wheel a predetermined number of steps, electromagnetic means providing a plunger pivotally connected to said actuating bar, said electromagnetic means adapted to actuate said bar through said plunger to advance said pawl over said wheel, said plunger having a notch formed in one side thereof to provide a shoulder, a blocking finger pivotally carried by said structure and having an end portion engageable with said shoulder, electromagnetic means for actuating said finger to engage said end portion with said shoulder to block said plunger to limit movement of the latter by said electromagnetic means, means for successively actuating said finger and said plunger, and electromagnetic holding means engageable with said wheel to hold said wheel against rotation in a direction opposite to the movement of said wheel by said pawl.

WILLIAM PATZER.
